UNITED STATES PATENT OFFICE

CHARLES R. TOST, OF CENTERDALE, RHODE ISLAND, ASSIGNOR TO THE HADLEY COMPANY, OF PROVIDENCE, RHODE ISLAND, A CORPORATION OF RHODE ISLAND

FASTENER FOR WATCH BRACELETS

Application filed April 5, 1929. Serial No. 352,666.

This invention relates to fasteners for separably attaching the ends of a bracelet or the like to the respective loops or bails of a wrist watch or similar article, and the principal object of the invention is to provide a detachable fastener of improved construction, comprising a holder for receiving such loop or bail and a complementary locking member hinged to the holder and constituting a cam lever operative concomitantly to clamp the loop against the holder and to confine the loop between the holder and the locking member.

Further objects reside in the structural features of a recommended embodiment of the invention as hereinafter described and illustrated in the accompanying drawings. In said drawings:

Fig. 1 is a front view of a wrist watch bracelet equipped with a pair of the improved fasteners;

Fig. 2 is a rear view thereof;

Fig. 3 is an enlarged side elevation of one of the fasteners;

Fig. 4 is an end view thereof;

Fig. 5 is a bottom view to larger scale showing one of the fasteners with its hinged locking element in open position; and

Fig. 6 is a central longitudinal section through an opened connector showing its holder received within the loop or bail of a wrist watch.

The wrist watch 11 indicated in Fig. 6 is intended to be representative of any watch or similar article having bails or loops 12 at its opposite sides for attachment to the ends of a wrist-encircling bracelet which may comprise one or more sections 13. When two such sections are provided, as shown, they may be separably or extensibly interconnected as by a folding attachment 14 or other suitable device. The bracelet may be made of any suitable flexible material such as a strap or straps of metal-mesh, leather or fabric; cords, thongs or ribbons; or other material having free ends adapted to be pinched and retained within the improved connectors. The particular shape, design or structure of these elements of the completed article is immaterial to the present invention.

Each of the fasteners for releasably attaching the free ends of the bracelet 13 to the respective loops or bails 12 preferably comprises a holder or jaw member including a flat portion 15 provided with upstanding sides or ears 16 having opposed openings 17, and a curved hook portion 18 having a central recess 19 at its outer edge; and a complementary locking member or cam lever pivoted as by studs 20 within the openings 17 and including a cam portion 21 and a lever portion 22, the latter having a central curved projection or tongue 23 receivable within the recess 19 when the jaw members are swung together into edgewise engagement. The interfitting ends of the jaws accordingly provide a closed hook having smooth curved inner and outer surfaces, the width of the hook being such that the interengaging jaws removably receive and retain the loops or bails 12.

The free end of the bracelet section 13 is removably received between the sides 16 of the holder and is retained therein by the gripping action of the cam member 21 upon closing the fastener. The end of said cam portion is preferably toothed or serrated, as at 24, to bite into the surface of the bracelet end (Fig. 3), positively to lock the parts together with a snap action as the lever arm 22 is closed upon the hook portion 18. The curved tongue 23 may have a notch or recess 25 to permit easy access by the finger nail for opening the fastener.

To attach the parts together, the curved hook 18 of the open fastener is passed through the bail or loop 12 of the watch or similar article, the bracelet end is inserted in the opposite end of the fastener, and the cam lever is snapped into place concomitantly to close the hook and pinch the bracelet between the plate 15 and the cam 21 of the fastener. Thus, the closed fastener is securely and positively locked against accidental opening; yet the pivoted cam lever may readily be swung out of locking engagement by the finger, as aforesaid, to release the bracelet and permit detachment of the bail.

A connector of fastener constructed as

above described is simple and economical to manufacture, easy to operate, and neat in appearance without sacrifice of operative efficiency. The article may be merchandised as

5 a separate unit or together with the bracelet upon which it may be fastened; in either case the detachable fastener may be applied to any common type of flexible bracelet and attached to a loop or bail, either rigid or flexible, carried by another article. Obviously, structural details of the device herein illustrated may be varied to suit particular purposes without departing from the essence of this invention as defined in the following claims.

10 15 I claim:

1. A fastener for separably connecting the end of a bracelet section to the bail of a wrist watch, comprising a jaw member having a hook at one end and a pair of upstanding ears adjacent its opposite end, and a cam lever pivoted between said ears and having a curved lever end to swing into edgewise engagement with said hook to enclose the bail therebehind, and a cam portion for gripping 20 a bracelet end received between said ears when the cam lever is snapped into closed position, thereby concomitantly to lock the bracelet and bail at opposite ends of the fastener, the hook and curved lever end having complementary tongue and recess portions, and one of said portions having an edge recess permitting the separation of the parts by the finger.

2. A fastener for separably connecting the end of a bracelet section to the bail of a watch, comprising a pair of hinged jaw members having correspondingly curved ends adapted to enclose the bail at one end of the fastener, the curved ends of the respective members having complementary tongue and recess portions 25 30 35 mutually interfitting in edgewise relationship when said ends are swung together, said hinged jaw member forming a continuous loop having substantially smooth inner and outer surfaces, and a cam portion formed on one of said members for pinching the bracelet section against the other member at the opposite end of the fastener when said members are closed.

3. A fastener for separably connecting the end of a bracelet section to the bail of a watch or the like, comprising a jaw member having upstanding side portions at one end and a curved hook portion at its opposite end, the hook portion having a central recess at its transverse edge, and a locking member pivoted between said side portions, and provided at one end with a cam portion for gripping a bracelet end received between said side portions when the locking member is swung to close the hook portion to enclose the bail behind the hook, the locking member having a projecting tongue at its opposite end formed to fit said recess in edgewise relationship,

the closed hook having substantially smooth inner and outer surfaces.

Signed by me at Providence, Rhode Island, this 2nd day of April, 1929.
